UNITED STATES PATENT OFFICE.

JOHANN G. PETERSON, OF JERSEY CITY, NEW JERSEY.

ELECTRIC SWITCH.

1,361,287.

Specification of Letters Patent. Patented Dec. 7, 1920.

Application filed December 31, 1917. Serial No. 209,714.

To all whom it may concern:

Be it known that I, JOHANN G. PETERSON, a citizen of the United States, residing at Jersey City, in the county of Hudson and State of New Jersey, have invented certain new and useful Improvements in Electric Switches, of which the following is a specification.

This invention relates to electric switches, and one of the primary motives I have in view is the provision of means of a simple and effective nature by which an operating device will be caused positively to move in a definite path which in the present case is a straight line. This operating device is operatively associated with what may be considered a controller which may take any convenient form. As a matter of preference, though not essentially, the controller is in the form of what is known as a rocker, while the operating device is in the form of a button. As a matter of further preference and especially in the type of switch which I have selected for illustration in the drawings accompanying and forming part of the present specification, this rocker is supported for oscillation between its ends, and there are two buttons associated therewith and connected to the rocker at opposite sides of its center of motion, one button being intended to effect the "on" relation of the switch, and the other the "off" relation through the intervention as is customary of spring or equivalent means, the button or buttons preferably presenting the primary power. As will be inferred I have illustrated a structure which meets my conditions in an eminently desirable manner, and to enable those skilled in the art to practise the invention I will set forth this rather in detail in the said description. As will be clear I do not restrict myself to this disclosure; I may depart therefrom in several respects within the scope of the invention defined by the claims following said description.

Referring to said drawings:

Figure 1 is a transverse vertical sectional view of a switch involving the invention.

Fig. 2 is a front elevation of the rocker and buttons, the spindle being shown by cross section and the full and dotted lines showing the parts in their two extreme positions.

Fig. 3 is a side elevation as seen for in-

stance from the left in Fig. 1 of the rocker and buttons, one of the latter being represented by dotted lines to indicate how it may be applied and removed.

Like characters refer to like parts throughout the several views.

As will be clear the invention may be incorporated in electric switches of various kinds; that shown is a two-button snap switch. The different parts of a switch comprising the invention except as to the push buttons, are inclosed in a boxing or casing such as that denoted in a general way by 2, which is provided with a cover usually in the form of a plate 3. This is merely one way of carrying the several parts. The cover or plate after the customary fashion is connected with the body of the boxing or casing 2, which is ordinarily of some insulating material as quite common in fact. In the boxing or casing are contacts as 4 and 5 mounted suitably therein and provided with means for the connection therewith of leads or conducting wires.

The bottom of the boxing or casing has connected therewith the support 6 which carries at or near its upper end the spindle 7. The spindle 7 loosely carries the rocker 8, and this rocker is one of several forms of controller embodying the invention. I term it "controller" as it is through its intervention that the action of the switching member is controlled or governed. The rocker has, of course, a central perforation for the passage of the spindle 7 and associated with it at opposite sides of its center of oscillation by buttons such as those denoted in a general way by 9 and 10 respectively, one button when advanced acting through the controller and intermediate parts to secure the "on" relation, the "off" condition being accomplished through the companion button.

The spindle 7 also loosely supports substantially centrally thereof the circuit controlling or switching member 11 provided with the blades 12 and 13 co-operative respectively with the contacts 4 and 5. In Fig. 1 the full lines show the circuit controlling or switching member 11 in the "off" relation. When it is in the "on" relation the ends of the blades 12 and 13 will be against the contacts 4 and 5 as understood. Loose on the spindle 7 is the sleeve 14 having a rigid connection

100

105

110

with the controller, actuator or rocker 8. Around the sleeve 14 is the body of the coiled spring 15, the terminals 16 and 17 of the spring bearing against the offset 18 of the upstanding arm 19, extending in an upward direction from the central upper portion of the rocker 8. The arm 20 also extends upward from the body of the circuit controlling member 11 and is provided with 10 an offset 21 complementary to the offset 18 and engaged by the free ends of the branches 16 and 17 when the switch is in its "on" and "off" positions respectively. The circuit controlling or switching member 11 is 15 also provided with a pendent extension 22 co-operative with the latch 23 having a detent portion 24 to be engaged by the pendent portion 22 when the circuit controlling or switching member is in its two extreme positions. The latch 23 is provided with a stud 25 fitting the arcuate slot 26 in the lower portion of the rocker 8.

The switch as I have already indicated is in the "off" relation in Fig. 1. To secure the "on" condition the following procedure may be adopted: The button 9 will be thrust down and this as I will hereinafter explain will impart a corresponding movement to the left branch of the rocker. On such movement of the rocker the walls of the slot 26 will engage the pin 25, thereby lowering the latch 23 and carrying the offset 24 from out of contact with the extension 22, thus releasing the switching member 11, so that the latter can be snapped to its closed position through the agency of the spring 15, as I will now explain. On the initial downward movement of the button 9 and the operating branch of the rocker in the manner set forth, the projection 18 will act against the branch 16 of the spring 15 and will thus tension or compress the spring, so that when the latch 23 releases the switching member 11 as I have just set forth, 45 the branch 17 of the spring by acting against the offset 21 can instantaneously snap or throw the switching member 11 to the closed position at which point it is clear the terminal portions 12 and 13 will engage the contacts 4 and 5. I have in rather a concise manner or as briefly as possible set forth a structure and mode of operation thereof, this structure being one of several with which my improvement can be incorporated in an effective manner. The improvement *per se* hinges upon the rocker 8 and buttons 9 and 10 or equivalents and certain coacting parts.

The rocker 8 has at opposite sides of its axis of oscillation the somewhat elongated slots 30 and 31, the ends of these slots being upon opposite arcs, although it is not always necessary that this be so. The inner walls 32 and 33 of the slots are arcuate, their arcs 60 as shown being struck practically and pref-

erably from the center of motion of the rocker. Said walls 32 and 33, therefore, may be considered as bulging or bowing outwardly. The outer walls of the slots consist of two portions denoted respectively by 70 34, 35, 36 and 37, the portions 34 and 35 and 36 and 37 presenting practically wedges, and they converge approximately on the transverse center lines of the respective slots 30 and 31.

Each of the buttons 9 and 10 comprises a body or shank portion as 38 and a head or button as 39, the shanks or bodies being like the rocker 8 of sheet metal, while the buttons 39 are of some non-conducting substance 80 such as common in the art. Each body at least for practically its major portion, is straight as a matter of preference, its upper end being turned outward as at 40 to act as an adequate support for the insulating 85 buttons 39. The outwardly turned portions 40 are furnished with the extensions 41 onto which the substance of the buttons is preferably molded, the extensions 41 terminating in laterally expanded portions 42 90 by which the buttons can be properly anchored to the extensions. The bodies or shanks 38 at their lower ends have open slots 43, the consequence being that the shanks or bodies are forked at their free or 95 lower ends, the slots being practically midway of the width of the respective bodies 38. In addition to these end slots 43, the bodies 38 have near their upper ends the lateral slots 44, what is shown as the upper wall of 100 the slots 44 being cut away or beveled off as at 45 to facilitate the connection of the bodies with the rocker 8.

To connect a body or shank as 38 with the rocker 8, the following procedure may be 105 adopted: The body or shank 38 in question with the button 39 applied thereto will be held at a slant and the lower portion of the body will be introduced into its slot for instance the slot 30 and the shank will then be 110 brought to an upright position and moved downward so that its lower forked end can be brought into straddling relation with the lower part of the rocker 8. As the shank or body 38 approaches the rocker, the upper 115 portion of the rocker or that above the slot 30 will enter into the slot 44, so that the shank 38 can be brought to an upright position and thus bring the bottom of the slot 44 practically against the front face of the 120 rocker after which the button 39 will be passed through its appropriate opening in the face plate 3. The same procedure will, of course, be followed with the other button 10.

It will be clear that owing to the construction described, the buttons 9 and 10 will with the parts be assembled and be maintained at all times in as nearly as practicable a right line which is an important con- 125 130

sideration. As one button moves down and the other up, the curved faces 32 and 33 will travel against the inner sides of the shanks 38, while the outer converging faces 34 and 35, and 36 and 37 will engage the outer faces of said shanks and thus positively and effectually guide the shanks in an approximately straight line which is a consideration of some importance. In reality the converging faces 34 and 35, and 36 and 37 respectively maintain the shanks in proper guide contact with the curved faces 32 and 33, so that the use of extraneous means for this particular purpose is unnecessary. It will, of course, be understood that the power of the shanks 38 is applied to the rocker 8 for oscillating the same through the upper walls of the slots 43, this obviously being effected in alternation.

One advantage in the straight line movement of the buttons 9 and 10 is the fact that these buttons can be closely fitted into guide openings in the face plate 3 so as to prevent dust and other foreign substances entering the casing by way of the openings through which the buttons pass. This same advantage follows when there is only one button. There is a further advantage in that the button or buttons, do not rock when operated or manipulated, on movement in straight paths or directions. Also where a mechanical device acts on the button, it is natural that if the button has a side movement that it is subjected to wear which would not be the case if the button moved in a straight direction and this applies whether there is a face plate or not.

What I claim is:

1. An electric switch comprising switching mechanism, means including a rocker, for controlling the action of the switching mechanism, and a button to operate the rocker, the rocker having a slot, the button straddling the rocker, and a walled part of the slot maintaining the button in an approximately straight path on its operation of the rocker.

2. An electric switch comprising switching mechanism, means including a rocker, for controlling the action of the switching mechanism, and a button straddling the rocker, the rocker having means to positively maintain the button in an approximately straight path on its operation of the rocker.

3. An electric switch comprising switching mechanism, means including a rocker, for controlling the action of the switching mechanism, and a button to operate the rocker, the rocker having a slot, the button extending into the slot and straddling the rocker, and a walled part of the slot maintaining the button in an approximately straight path on its operation of the rocker.

4. An electric switch comprising switching mechanism, means including a rocker, for controlling the action of the switching mechanism, a button to operate the rocker, the rocker having a slot, a walled part of which constitutes means for maintaining the button in an approximately straight path on the operation of the rocker by the button, and a face plate having a guide opening to receive said button for back and forth movements.

5. A switch comprising switching mechanism, means including a rocker for effecting "on" and "off" movements of the switching mechanism, and buttons straddling the rocker for operating the same in opposite directions, the buttons having sliding engagement with the rocker at opposite sides of the axis of oscillation thereof, and the rocker having means to maintain the buttons in an approximately straight line on their operation of the rocker.

6. A switch comprising switching mechanism, means including a rocker, for controlling the action of the switching mechanism, and a lever to operate the rocker, the button straddling the rocker and having a sliding engagement therewith, and the switch having means to positively cause the button to follow a predetermined path.

7. An electric switch comprising switching mechanism, means including a rocker, for controlling the action of the switching mechanism, buttons to operate the rocker in opposite directions, the rocker having slots at opposite sides of its axis of motion, the buttons extending into slots and slotted to straddle the rocker, walled parts of the respective slots maintaining the buttons in approximately straight paths on the operation of the rocker.

8. A switch comprising switching mechanism, means including a rocker for controlling the action of the switching mechanism, the rocker having a slot, one wall of which is on an arc struck from the center of motion of the rocker, and the other wall of which has portions which converge approximately at the center of the arcuate portion of the slot, and a button to engage and operate the rocker, the walls of the slot being in contact with the button to maintain the same in an approximately straight line on its operation of the rocker.

9. A switch comprising switching mechanism, means including a rocker for controlling the action of the switching mechanism, the rocker having slots at opposite sides of its center of motion, the inner walls of the slots being on arcs struck from the center of motion of the rocker, and the outer walls of which have portions which converge approximately at the center of the arcuate portion of the slots, and buttons to engage and operate the rocker, the walls

of the slots being in contact with the buttons to maintain the same in an approximately straight line on their operation of the rocker.

10. A switch comprising switching mechanism, means including a rocker for controlling the action of the switching mechanism, the rocker having a slot, one wall of which is on an arc struck from the center of motion of the rocker, and the other wall of which has portions which converge, and a button to engage and operate the rocker, the walls of the slot being in contact with the button to maintain the same in an approximately straight line on its operation of the rocker.

11. A switch comprising switching mechanism, means including a rocker for controlling the action of the switching mechanism, the rocker having a slot, one wall of which is on an arc struck from the center of motion of the rocker, and the other wall of which has portions which converge and a button straddling and engaging the rocker to operate the same, the walls of the slot being in contact with the sides of the button to maintain the same in an approximately straight line on its operation of the rocker.

12. An electric switch comprising switching mechanism, means including a rocker, for controlling the action of the switching mechanism, a button to operate the rocker, the rocker having a slot, the button straddling the rocker and a walled part of the slot maintaining the button in an approximately straight path on its operation of the

rocker, and a member having an opening through which the button extends.

13. A switch comprising switching mechanism, means including a rocker for controlling the action of the switching mechanism, the rocker having a slot, one wall of which is on an arc struck from the center of motion of the rocker and the other wall of which has portions which converge approximately at the center of the arcuate portion of the slot, a button to engage and operate the rocker, the walls of the slot being in contact with the button, and a fixed part having an opening through which the button extends.

14. A switch comprising switching mechanism, means including a rocker, for controlling the action of the switching mechanism, the rocker having slots at opposite sides of center of motion, the inner walls of the slots being on arcs struck from the center of motion of the rocker and the outer walls of which have portions which converge approximately at the center of motion of the arcuate portions of the respective slots, buttons to engage and operate the rocker, the walls of the respective slots being in contact with the button, and a fixed member through which the buttons slidingly extend.

In testimony whereof I affix my signature in the presence of two witnesses.

JOHANN G. PETERSON.
